UNITED STATES PATENT OFFICE.

ISAAC ARTHUR HILLS, OF GRAND RAPIDS, MICHIGAN.

DESIGN FOR A BOOK END.

Application filed June 29, 1927. Serial No. 22,598. Term of patent 3½ years.

To all whom it may concern:

Be it known that I, ISAAC ARTHUR HILLS, a citizen of the United States, residing at No. 1157 Plainfield Avenue N., Grand Rapids, in the county of Kent and State of Michigan, have invented a new, original, and ornamental Design for a Book End, of which the following is a specification, reference being had to the accompanying drawing, forming a part thereof, in which—

I claim:

The ornamental design for a book end substantially as shown.

ISAAC ARTHUR HILLS.
